UNITED STATES PATENT OFFICE

91,983

DESIGN FOR A BOILER CASING

Victor Civkin, Cleveland, Ohio, assignor to General Electric Company, a corporation of New York

Application February 6, 1934, Serial No. 50,650

Term of patent 14 years

To all whom it may concern:

Be it known that I, VICTOR CIVKIN, a citizen of the United States, residing at Cleveland, in the county of Cuyahoga, State of Ohio, have invented a new, original, and ornamental Design for a Boiler Casing, of which the following is a specification, reference being had to the accompanying drawing, forming a part thereof.

The figure is a front perspective view of a boiler casing showing my new design.

I claim:

The ornamental design for a boiler casing substantially as shown.

In witness whereof, I have hereunto set my hand this 2nd day of February, 1934.

VICTOR CIVKIN.
